BED SCREEN

Paul N. Gregory, Nampa, Idaho

Application December 3, 1945, Serial No. 632,508

7 Claims. (Cl. 135—5.1)

1

The present invention relates to a portable screen assembly which may be used in hospitals to shield the occupant of a bed, for instance, while medical or other attention is being given in a ward, or to generally insure privacy for a patient.

While the particular use referred to above is contemplated, it will be apparent as the description progresses that the invention would be useful for other similar purposes and in other situations.

While movable screens are now used in hospital wards to provide some degree of privacy, they are usually quite inadequate and expose the patient to much annoyance and discomfort. Generally speaking, the screens now in use are only adequate to shield one side of a bed, and the attendants are not likely to take the trouble to move up several screens in order to give a patient the complete privacy he may require. For this reason, it is very desirable to have a unitary assembly which will supply the complete privacy desired.

A principal object of the invention is to provide such a screen assembly of light construction which can be placed around a hospital bed when desired and having parts which can be conveniently and compactly housed when the screen is not in use so that the assembly may be moved to another location or placed aside in a corner of a ward or in a corridor of the hospital.

The assembly illustrated comprises a movable housing or cabinet-like structure which is adapted to shield one end of a bed, preferably the foot thereof, and extensible side curtain members which can be adjustably positioned along the sides of the bed to any length desired. The construction is such that when the screen is no longer needed at a particular location, the extensible side curtains may be retracted into the housing to be carried by the latter, at which time the entire assembly may be wheeled away.

In the drawings, which are illustrative of a preferred form of the invention, and which are in no sense restrictive:

Figure 1 is an isometric view of the assembly, showing the manner in which side curtains may be retained housed within the cabinet portion of the assembly, or extended to shield one side of the bed.

Figure 2 is a side elevational view of a portion of the apparatus, showing the manner in which a side curtain is supported by one of the movable standards.

Figure 3 is a lateral vertical sectional view

2

through one end of the housing, taken on about the line 3—3 of Figure 1, showing the preferred pulley arrangements within the housing for retracting the cables for a side curtain.

5 Figure 4 is a partial horizontal sectional view taken along the line 4—4 of Figure 3.

Figure 5 is a top plan view of one of the standard supporting brackets on the housing, showing the standard supported thereon.

10 Figure 6 is a side elevational view of the bracket arrangement of Figure 5, and

Figure 7 is a view similar to Figures 2 and 3 of a modified pulley arrangement for retracting the side curtains.

15 Figure 8 is a partial end view showing one arrangement for supporting the standard on the cabinet.

Referring to Figure 1, the main element of the assembly is a cabinet-like end structure made of 20 metal, wood, plywood, or light composition material and having a top wall 10, opposite end walls 12 and 13, a bottom wall 14, and a rear or outer wall 16. The cabinet structure is open on its inner side, this being the face of the structure which is presented to the head or foot of the bed when the assembly is in position for use. Any available space within the cabinet may be used for storage of blankets, linens, medicants or the like. The housing may be of any appropriate length, depending on the beds or other objects to be screened, but it should be sufficiently longer than the width of a bed so that when the side curtains are extended, as hereinafter described, adequate space will be left on each side of the bed inside of the curtain extensions, to permit attendants to move about within the curtains while treating the patient. The cabinet should be long enough, for instance, to provide a space of one foot on each side of the bed when side curtains are extended, or a space of two feet on one side of the bed when desired. While I have shown the housing in square or box-like form, it will be understood that this housing may have its outer and end walls rounded to eliminate 35 sharp corners, or it may be of any other shape to enhance its utility or attractiveness.

The housing is supported in spaced relation to the floor by a pair of legs 18 at one end and by wheels 20 at the other end thereof, the wheels 50 being mounted on a shaft 22 carried by suitable brackets 24 depending from the bottom 14 of the housing. While plain legs are shown in the drawings, they may be made of any desired shape or material, such as of twisted wire, to add to the attractiveness of the cabinet design. Instead of

wheels, ordinary castors might be used on a pair of additional legs at the end of the cabinet where the wheels are located. By means of a handle 26 attached to the end panel 12 of the housing, the latter may be tilted so that it is entirely supported on the wheels 20, and may then be moved about the hospital or through the wards as desired. The legs 18 are of such length and the cabinet structure is of such depth that when properly positioned, the end of a bed is effectively shielded, with resulting privacy for the occupant.

When the housing has been disposed across the head or foot of a bed, the sides of the bed may be shielded by an extensible curtain 28 supported between the housing and a movable standard 30, the latter being any form of upright post having a floor base 35 of sufficient weight and area to insure that the standard will be self-supporting in an upright position. The curtain 28 may be made of any appropriate material, such as light or heavy fabric, cloth or canvas, and it is slidably carried on upper and lower flexible cables 31 and 32. The curtain is loosely secured to the cables by conventional connecting rings 34 which are large enough to slide easily along the cables. As best shown in Figure 2, the outer ends of the cables 31 and 32 are secured to an end rod 36 in any suitable manner, the drawings showing the ends of the cables passing through holes in the rod and having their outer ends knotted as at 38. The vertical outer edge of the curtain may also be slidably attached to the rod 36 by conventional securing rings or this outer edge may simply be formed into a sleeve fitting around the rod.

As illustrated in Figure 1, suitable brackets are secured to the end walls 12 and 13 of the cabinet or housing, comprising upper and lower open aligned sockets 40. These sockets are adapted to receive a standard and to support the latter with its base elevated from the floor by means of spaced collars 42 on the standard, the collars being formed to rest in the sockets 40 as shown in Figures 5 and 6. The sockets 40 are located at the upper and lower inner corners of the panels 12 and 13, and their open sides 43 are large enough to pass the standards 30 when the latter are hung on the sockets by their collars 42. The collars 42 are so positioned that each standard is supported on the cabinet with its base 35 off of the floor as shown at the left hand end of the cabinet in Figure 1.

While I have shown the brackets 40 secured on the end panels 12 and 13, they may be secured at any convenient points near the inner corners of the cabinet, such as on the inner edges of the top and bottom panels 10 and 14 near the corners of the cabinet.

By reason of the above construction, the curtains 28 may be retracted into the cabinet and the standards 30 hung on opposite ends thereof, at which time the entire assembly may be wheeled to any desired location. While the upright curtain rods 36 may be removably secured to the standards 30 by hook and eye connections 46 as shown in Figure 2, it is not necessary that the curtain rods be removed from the standard when the latter is supported on the cabinet. The curtains are at all times ready to be extended by simply lifting the standards and releasing their collars from the sockets on the cabinet, and moving them outwardly to draw the curtain from its compartment in the housing. As the collars 42 are shaped to rest in depressions in the sockets, as shown in Figure 6, the standards will not be displaced until positively lifted and removed. It

will be obvious that the side curtains may be extended to any desired length, concealing only a part or all of the bed.

At each end of the interior of the cabinet there is a front curtain chamber formed by a vertically disposed metal channel or angle insert member as illustrated in Figure 4. This member has a vertical side wall 50 and a connected vertical back wall 52, these walls being secured to the top, bottom and end panels of the cabinet by any suitable flanged connections such as at 54. The cabinet may be fabricated of light metal, and the angular members constituting the plates 50 and 52 may likewise be of metal, in which case they may be welded to the top, bottom, and end panels of the cabinet.

As best illustrated in Figures 3 and 4, the provision of the L-shaped member at opposite ends of the interior of the cabinet results in the formation of open faced curtain gathering compartments 60 on the inner side of the cabinet, the rear walls 52 thereof being the forward walls of pulley compartments 62. The rear wall of each pulley compartment is the outer panel 16 of the cabinet.

As the compartment and pulley arrangement is duplicated at each end of the cabinet, a description of the construction at one end thereof will suffice. Secured on the inner face of the end wall 13 of the cabinet, and within the pulley compartment referred to, is an upper double pulley 64. This pulley is substantially in alignment with an opening 68 through the rear wall 52 of the curtain compartment 60 near the top of the cabinet. There is also a lower single pulley 66 fixed on the inner face of the end wall 13 and within the pulley compartment 62 substantially in alignment with a hole 70 in wall 52 adjacent the bottom of the cabinet.

In the arrangement shown in Figures 2 and 3, the top curtain cable 31 passes through the hole 68, and over the inner sheave of the double pulley 64, whereas the lower curtain cable 32 passes through the lower hole 70 in the plate 52, beneath the single pulley 66, and thence over the outer sheave of the double pulley 64. Each of cables 31 and 32 thence passes under appropriate and respective sheaves of a double moving pulley 72 carrying a weight 74, and thereafter the cables extend upwardly and are secured to the top of the cabinet in any suitable way as at 78. Pulley 72 and weight 74 are thus supported for up and down movement on the cables. It will be understood that in this arrangement, a separate cable is provided for the top and bottom of the curtain 28, the top cable simply passing over pulley 64 and under pulley 72 to be secured to the top of the cabinet, whereas the bottom cable 32 passes under pulley 66, over pulley 64, under pulley 72, and thence is secured to the top of the cabinet adjacent to the securing point of the terminal end of the upper cable. The pulley 72 and weight 74 are at their lowermost position when the curtain is housed within compartment 60 of the cabinet, it being understood that at this time, the corresponding standard 30 would be supported on the cabinet in the brackets 40. When the screen has been placed across the end of a bed, one or both of the side screens are positioned by simply lifting standard 30 off of its supports and carrying it along the side of the bed, thus automatically withdrawing curtain 28 from its compartment by extending cables 31 and 32 and elevating the pulley 72 and weight 74 in the pulley compartment 62. If desired, the inner edge of the curtain may be secured to the

wall 52, to insure that the curtain is stretched when extended, but this arrangement is not essential. The curtain may be pulled throughout any desired length of the bed, depending merely on the positioning of the standard 30. When the side curtain is no longer desired, the standard 30 is lifted from the floor, moved inwardly toward the cabinet and hung on the brackets 40. During this movement, the curtain is automatically and neatly retracted into the compartment 60 by reason of the lowering of the weight 74, which in turn, draws the cables 31 and 32 through their respective holes 68 and 70. During this retracting action, the curtain is "gathered" in the compartment 60, as the rings 34 will not pass through the holes 68 and 70, but will build up against one another around the cable, but on the outside of the plate 52.

It will be obvious that variations of the preferred pulley arrangements shown may be used to retract the curtains. In the reduced and partially diagrammatic view of Figure 7, a modified arrangement is disclosed wherein the cables 31 and 32 are continuous, in the sense that they are connected at their inner ends or are extensions of one another. In this arrangement, there are two single upper pulleys 80 and 82 secured to the end panel 13 near the top of the pulley compartment 62, a single pulley 84 fixed to the end panel adjacent the bottom of this compartment, and a moving pulley 86 having a weight 88 thereon positioned between pulleys 80 and 82, and adapted to move upwardly and downwardly in the pulley compartment. In this arrangement, the cable 31 passes through the upper cable hole 68, over the pulley 80, under pulley 86, over pulley 82, and thence downwardly around the pulley 84 and through the lower hole 70 in plate 52, the cable being designated at this point as the lower cable 32. With this modified cable arrangement, the standards and side curtains are operated in substantially the same manner as previously described.

The present invention offers complete privacy for doctors, nurses, and patients, comprising in reality a portable room within a ward. It is of such light construction, that it may be easily moved about, and it can be set up for use in much less time than would be required for three separate screens as now employed. The bedside space may be quickly adjusted by moving the screen. When not in use, the side curtains of the screen are protected from dust in their compartments. They may be conveniently removed for laundering.

It will be apparent that I have provided a screen assembly of great utility, yet characterized by pronounced simplicity of construction and convenience of operation. Because of its compactness and simplicity, hospital attendants will be encouraged to use the screen with resulting increase in comfort for the patients. While use in hospitals will be most important, the assembly may be useful at other places, both in and out of doors where a person may wish to recline in privacy. At institutions where there are a great many invalid or semi-invalid cases, this assembly will contribute greatly to their comfort and to their health.

I claim:

1. A screen assembly comprising a housing adapted to be positioned adjacent one end of an object to be shielded, a standard movable from and toward said housing, a curtain supporting cable extending between said standard and said

housing when the former is spaced from the latter, a curtain carried on said cable which serves to shield one side of the object, and means in said housing for retracting said cable when said standard is moved toward said housing.

2. A screen assembly comprising a housing, adapted to be positioned adjacent one end of an object to be shielded, a curtain compartment in said housing, a standard movable from and toward said housing, top and bottom curtain supporting cables extending respectively between the upper and lower ends of said standard and said housing when the former is spaced from the latter, a curtain carried on said cables which serves to shield one side of the object and means in said housing for retracting said cables and said curtain into said compartment when said standard is moved toward said housing.

3. A screen assembly comprising a mobile housing, adapted to be positioned adjacent one end of an object to be shielded, a standard movable from and toward said housing, said standard having a base which rests on the floor and being self-supporting thereon, a curtain supporting cable extending between said standard and said housing when the former is spaced from the latter, a curtain carried on said cable which serves to shield one side of the object, means in said housing for retracting said cable when said standard is moved toward said housing, and means on said housing for supporting said standard in upright position thereon with the base of the standard elevated above the floor, whereby the assembly may be moved as a unit when said curtain is retracted, and said standard is supported on said housing.

4. A screen assembly comprising a housing, adapted to be positioned adjacent one end of an object to be shielded, a curtain compartment in said housing, a standard movable from and toward said housing, a curtain supporting cable extending between said standard and the curtain compartment of said housing when said standard is spaced from said housing, a curtain slidably attached to said cable which serves to shield one side of the object, and means in said housing for retracting said cable when said standard is moved toward said housing, said compartment having means for slidably gathering the curtain on said cable when said cable is retracted.

5. A screen assembly comprising a housing adapted to be positioned adjacent one end of an object to be shielded, a curtain compartment in said housing having a rear wall with a cable opening therein, a cable passing through said opening and adapted to be extended from said housing, a curtain loosely carried on said cable which serves to shield one side of the object, when said cable is extended, and means in said housing beyond said wall for retracting said cable through said opening, said wall gathering the curtain in said compartment as said cable is retracted.

6. A screen assembly for beds and similar objects comprising a housing of length substantially greater than the width of the object to be screened and which is of height to shield one end of the object, a pair of standards movable toward and from the ends of said housing, curtain supporting cables extending between said standards and the ends of said housing when said standards are spaced from said housing on each side of the object, curtains supported on said cable which serve to shield opposite sides of the object, and means in said housing for retracting said cables

when said standards are moved toward said housing.

7. A screen assembly for beds and similar objects comprising a mobile cabinet, adapted to be positioned at one end of the object to be shielded and being of length greater than the width of the object, curtain compartments at opposite ends of said cabinet, said compartments having rear walls with cable openings therein, a pair of standards movable from and toward the ends of said housing, curtain supporting cables passing through said openings and extending between said standards and said housing when the former are spaced from the latter, curtains loosely carried on said

cables which serve to shield opposite sides of the object, means in said housing behind said wall for retracting said cables when said standards are moved toward said housing, said wall gathering the curtains in said compartment as said cables are retracted, and cooperating means on said cabinet and said standards for supporting said standards in upright position thereon with the bases of said standards elevated above the floor, whereby the assembly may be moved as a unit when said curtains are retracted and said standards are supported on said housing.

PAUL N. GREGORY.
